UNITED STATES PATENT OFFICE.

ANTON VOMELA, OF ST. PAUL, MINNESOTA.

HEEL-FASTENING MEANS.

1,354,356.

Specification of Letters Patent. Patented Sept. 28, 1920.

Application filed March 8, 1920. Serial No. 364,127.

To all whom it may concern:

Be it known that I, ANTON VOMELA, a citizen of the United States, residing at St. Paul, in the county of Ramsey and State of Minnesota, have invented certain new and useful Improvements in Heel-Fastening Means, of which the following is a specification.

This invention relates to improvements in fastening means for shoe heels and more particularly for heels used on ladies' shoes, and especially for the high heels known as French heels.

An object of the invention is to provide improved anchoring means for heels, whereby the pull of the heel in its tendency to separate from the sole will be distributed over a comparatively large area of the insole, special consideration having been given to the strict avoidance of centering any appreciable amount of stress on the upper and counter surrounding the heel. In some forms of anchoring means now in use a large part of the stress tending to separate the heel from the shoe is brought to bear on the lap of the upper over the insole resulting in fracture of the upper at visible points adjacent the heel.

A further object of the invention is to provide heel fastening means which may be cheaply manufactured and easily applied and which will entail no radical changes in the manufacture of shoes.

To this end the invention consists of the construction, combination and arrangement of parts hereinafter described and claimed.

In the drawings:

Figure 1 is a perspective view of the invention applied to a heel of a ladies' shoe, the heel being partly broken away.

Fig. 2 is a sectional view on line 2-2 of Fig. 1.

Fig. 3 is a sectional view on line 3-3 of Fig. 2.

Fig. 4 is a perspective view of the heel end of the insole and main sole illustrating the initial step in applying the invention, and

Fig. 5 is a perspective view of the heel end of the main sole showing the invention applied on ordinary heels or military heels.

In the drawings A represents the upper of a ladies' shoe, B the sole thereof and C the insole underlying the latter. D represents a finish covering overlying the sole B and extending over the forward curved

face of the heel. Between the sole and insole and secured to the latter as by means of pegs or nails 1 and extending longitudinally of the sole is the heel anchor or fastening member F. The heel anchor comprises a comparatively long narrow plate-like shank 2 bent upon itself at its rear end (relative to the shoe) at an acute angle so as to form a comparatively short hook member extending forwardly. The hook member is formed with a centrally disposed bifurcation 3 extending toward the bend 4 of the anchor, whereby are formed two forwardly extended tines or fingers 5 each having near its free end a hole 6 adapted to receive suitable nails whereby the tines may be nailed to the insole C in a manner to leave a suitable space between the underside of the tines and the sole B for the purposes hereinafter to be explained. In Fig. 5 the tines are shown nailed in this manner.

In Fig. 2 of the drawings is shown approximately the positions assumed by the insole and the sole when the heel is permanently secured thereto. G represents the usual counter positioned between the upper A and the usual lining H. The upper, counter and lining are flanged inwardly to form the horseshoe shaped lips 7, 8 and 9 respectively, these lips being superposed one upon another and overlying collectively the insole, as indicated in Fig. 2. The anchor F is so positioned longitudinally on the insole as to bring the bend 4 thereof well up to the bend constituting the base of the superposed lips.

Piercing the hook and shank member adjacent the bend 4 of the anchor is the elongated opening 10 adapted to receive one or more nails, as shown in Fig. 4, whereby, as shown in Fig. 2, the insole, anchor and said three superposed lips may be firmly fastened together by means of nails 11 and 12, the latter tending to prevent lateral shifting of the anchor and opening of the hook portion thereof. Thus the upper together with the counter and lining are firmly secured to the insole and anchor F.

Permanently positioned in the concave underface 13 is the headed pin or screw 14, the head 15 thereof extending a distance from the face 13 so that the shank of the screw may freely enter the bifurcation 3 of the anchor member. The screw is positioned relative to the rearmost edge 16 of the heel so that the shank thereof will enter the bifur-

cation a distance beyond the nail holes 6 in the tines 5. As indicated in Fig. 4 of the drawings the sole B is cut away along its edges so as to fit loosely within the space 5 described by the edges of the superposed lips 7, 8 and 9 thereby leaving the outer face of the lip of the upper exposed to serve as a gluing surface to contact with the undersurface 13 of the heel. To further present a 10 rounding surface to fit into the concave face 13 of the heel the sole B is chamfered to form a continuous knife edge 16' when the parts are positioned as shown in Fig. 1. The heel is slid longitudinally rearwardly, the 15 screw 14 entering the bifurcation 3 until the edge 16 of the heel is properly placed, a quantity of glue having previously been placed over the parts. The soles are now 20 nailed to the heel, as indicated in Fig. 2, the insole and the shank 2 of the anchor all conforming to the concavity of the undersurface of the heel, the glue filling any interstices which may be formed. In the process 25 of nailing into the heel from the inside of the shoe the nails in the holes 6 of the tines may be further crushed or clenched whereby the tines will be bent downwardly, as indicated in dotted lines in Fig. 5, thereby firmly locking the screw head in the bifurcation.

30 In the act of walking there exists a constant tendency to pull the heel at its rearmost edge 16 away from the upper and a rigid unyielding fastening at this point would result in fracture of the leather.

35 It will be noted that the screw 14 is positioned a distance forward of the bend 4 of the anchor, the direction of the pull tending to separate the heel from the sole being indicated by the arrows Fig. 2. If now the 40 glued or lightly nailed joint to the rear of the screw should yield the heel and sole would not separate because the anchor portion between the screw and bend would yieldingly resist separation and thereby prevent 45 rupture of the leather.

I claim:

1. In heel fastening means, the combination with the heel and the body of the shoe, of a strap of metal firmly secured flatwise on the bottom of the body of the shoe at the heel portion thereof, the rear portion of said strap being formed with a hook the jaw thereof facing forwardly the free end of said hook being bifurcated, locking means on the heel adapted to engage said hook to be slid into said bifurcation to

lock the heel to said body of the shoe, said hook being perforated to the rear of said bifurcation whereby the body of the shoe may be firmly secured thereto irrespective 60 of the heel for the purpose set forth.

2. In a heel anchor, the combination with the heel, a locking member on the heel, and the heel portion of the body of the shoe the latter consisting of an insole, an outer sole 65 overlying said insole and a counter and upper overlapping the edge of said insole, of a strap of metal secured to said insole and overlaid by said outer sole said strap being formed with a hook adapted to interlockingly engage said locking member of the heel to hold the latter positioned on the shoe body, a portion of said strap extending rearwardly beyond said locking member when the latter is in interlocked position and extending between the insole and said overlaps 70 of the counter and upper, said rearwardly extending part having provision whereby it may be collectively secured together with the insole and said overlaps.

3. In a heel anchor, the combination with the heel having a projecting headed pin, and the heel portion of the body of the shoe the latter consisting of an insole, an outer sole 75 overlying said insole and a counter and upper overlapping the edge of said insole, of a strap of metal secured to said insole and overlaid by said outer sole said strap being formed with a forwardly opening hook 80 adapted to interlockingly engage said headed pin of the heel to hold the latter positioned on the shoe body, the bend of the hook end of said strap extending between the insole and said overlap of the counter and upper for the purpose set forth.

4. Heel fastening means consisting of a metallic member secured flatwise on the bottom of the body of the shoe at the heel portion thereof and being formed so that a rear portion thereof relative to the shoe will be 100 spaced from said bottom, a coöperating member on the heel adapted to extend under said spaced portion at a position a distance from the rearmost end of said metallic member to lock the heel to the shoe body, and provision on said metallic member for fastening said spaced portion to the shoe body at positions in front and to the rear of said coöperating member.

In testimony whereof I affix my signature. 110

ANTON VOMELA.
